US00D876254S

(12) **United States Design Patent** (10) Patent No.: **US D876,254 S**
(45) Date of Patent: **** Feb. 25, 2020**

(54) **ENVIRONMENTAL MONITORING DEVICE**

(71) Applicant: **PILLAR TECHNOLOGIES, INC.**,
New York, NY (US)

(72) Inventors: **Matthew Jean-Marie Joseph Joyal**,
New York, NY (US); **Jesse S. Kruska**,
Westport, CT (US); **Alexander**
Messersmith Schwarzkopf, New York,
NY (US); **James Sener**, Glastonbury,
CT (US); **Scott Smith**, Hartford, CT
(US); **Sean Peter Iacobone**, New York,
NY (US)

(73) Assignee: **Pillar Technologies, Inc.**, New York,
NY (US)

(**) Term: **15 Years**

(21) Appl. No.: **29/662,710**

(22) Filed: **Sep. 7, 2018**

Related U.S. Application Data

(63) Continuation of application No. 29/612,914, filed on
Aug. 4, 2017, now Pat. No. 830,206, which is a
continuation of application No. 15/349,811, filed on
Nov. 11, 2016, now Pat. No. 9,986,313.

CLAIM

The ornamental design for an environmental monitoring
device, as shown and described.

DESCRIPTION

FIG. 1 is a front plan view of a first embodiment of an
environmental monitoring device design;
FIG. 2 is a left side view of the embodiment shown in FIG.
1;
FIG. 3 is a rear plan view of the embodiment shown in FIG.
1;
FIG. 4 is a right side view of the embodiment shown in FIG.
1;
FIG. 5 is a top plan view of the embodiment shown in FIG.
1;

(Continued)

FIG. 6 is a bottom plan view of the embodiment shown in FIG. 1; and,

FIG. 7 is a top, right perspective view of the embodiment shown in FIG. 1.

The broken lines shown represent unclaimed subject matter and form no part of the claimed design.

1 Claim, 7 Drawing Sheets
